LONG STROKE PUMPING OUTFIT

Filed Jan. 16, 1930

UNITED STATES PATENT OFFICE

ELIJAH D. SMITH AND CHARLES S. MCINTYRE, OF DRUMRIGHT, OKLAHOMA

LONG-STROKE PUMPING OUTFIT

Application filed January 16, 1930. Serial No. 421,212.

The present invention relates to improvements in pumping apparatus.

An object of this invention is to provide means whereby the normal stroke of the pumping apparatus may be substantially increased without in any way changing the structure of the pumping apparatus.

Another object of this invention is to provide an attachment which may be added to an oscillating pump apparatus by means of which the pumping stroke will be materially increased.

A further object of this invention is to provide a device of this character which is readily and cheaply manufactured and which will not materially increase the cost of the pumping apparatus.

The above and various other objects and advantages of this invention will in part be described in and in part be understood from the following detailed description of the present preferred embodiment, the same being illustrated in the accompanying drawing wherein:

Figure 1 is a fragmentary detailed side elevation of a device constructed according to the preferred embodiment of this invention;

Figure 2 is a detailed front elevation of the device; and

Figure 3 is a fragmentary top plan view of the adjustable connecting bars.

Referring to the drawing wherein like numerals of reference designate corresponding parts throughout the several views, the numeral 10 designates a supporting post or member upon the upper end of which an oscillating beam member 11 is mounted. A power wheel 12 which is operated from a suitable source of power supply is rotatably carried by a supporting member 13 which is positioned in spaced relation to the supporting post 10, and an outstanding crank member 14 is carried by the shaft 15 which is rotatably carried by the bearing support 13.

A pitman or connecting bar 16 is loosely mounted at one end of the offset crank member 14 and at the other or upper end is pivotally secured to the inner end portion of the

beam member 11 as at 17. In the device at present in use, the oscillating movement of the beam member 11 is dependent upon the stroke of the offset crank member 14 and in order to increase the oscillating movement of the beam it is either necessary to increase the stroke or to change the position of the pivotal support or fulcrum 18 of the beam. In most cases it is not advisable to change the position of the fulcrum 18, and it is exceedingly difficult to change or lengthen the stroke produced by the crank 14. However, an increased pumping stroke is accomplished by means of a long stroke attachment which is secured at one end to the crank member 14 or to the lower end portion of the pitman 16. The long stroke attachment comprises a plate bolt 19 which may be secured to the pitman 16 at any desired point along the pitman but preferably is adapted to have the offset crank member 14 extend therethrough so that the full stroke of the crank member will be utilized.

A U-shaped plate 20 or the like is mounted on the outer end portion of the oscillating beam 11 and is mounted in inverted position being provided with gudgeons or shafts 21 or the like outstanding from the lower ends thereof.

A pair of sprocket wheels 22 are secured to the outer end portions of the shafts 21 and are positioned in spaced relation to the opposite face portions of the beam member 11. A pair of chain strands 23 are adapted to ride over the sprockets 22 and are secured at one end to a transverse bar 24 and at the opposite end to a pair of turnbuckles or connecting members 25. The connecting members 25 are adapted to extend about the opposite side portions of the supporting post 10 and are secured at the opposite ends to a second transverse bar 26 which is swiveled or rotatably mounted therein.

A clevis or forked bar member 27 is secured at one end to the transverse swiveled member 26 and at the opposite end is mounted in the plate member 19. If desired, the plate member 19 may be provided with a plurality of openings 29 so that any desired stroke may be obtained.

A reciprocating pumping rod or member 30 is adapted to be secured at the upper end portion thereof in the transverse bar 24 and carries at the lower end portion thereof the conventional pumping members. If desired, the sprocket member 22 may be substituted by a wheel member and the chain strands 23 substituted by suitable flexible members in the form of belts or the like, but in the preferred embodiment of this invention, due to the amount of pull exerted by the pumping apparatus, the sprocket members 22 and the chain strands 23 have been found to accomplish the desired result and to withstand the strain under which these members are constantly placed.

In the use of this device, the oscillating pumping apparatus is adapted to be operated in the conventional manner. When the power wheel 12 is rotated thereby rotating the crank 14, the eye bolt 19 is operatively swung with the movement of the pitman 16. The swinging movement of the eye bolt 19 will coactively oscillate the connecting bar 27 and coactively operate the chain strands 23 so that on the downward stroke of the beam member 11, the cable or pump rod 28 will be permitted to move downwardly substantially an additional distance equal to the distance between the eye bolt 19 and the axial shaft member 15. In like manner, the upward stroke of the pump 28 will be increased the same distance.

It will, of course, be understood that various changes and modifications may be made in the details of construction and design of the above specifically described embodiment of the invention without departing from the spirit thereof, such changes and modifications being restricted only by the scope of the following claims.

What is claimed is:—

1. In combination with an oscillating beam having power means, flexible means secured at one end to said power means and at the opposite end to a pump rod, said flexible means being adapted to reciprocally engage said oscillating beam whereby to increase the stroke thereof imparted to said pumping rod, and means carried by said beam and engaging said flexible means whereby to permit reciprocation of said flexible means coactively with the oscillation of the beam.

2. In pumping apparatus, a power wheel, an upright supporting member spacedly mounted with respect to said power wheel, an oscillating beam fulcrumed on said support, connecting means for connecting said beam and said power wheel, flexible means secured to said connecting means and reciprocally engaging said oscillating beam, and means carried by said beam and engaging said flexible means whereby to permit reciprocation of said flexible means coactively with the oscillation of the beam.

3. In pumping apparatus, a supporting member, an oscillating beam fulcrumed on said supporting member, power means spacedly positioned with respect to said supporting means, a pitman secured at one end to said oscillating beam and at the opposite end to said power means, a wheel rotatably mounted on said oscillating beam adjacent the outer end portion thereof, flexible means engaging about said wheel and adapted to be secured at one end to a reciprocating element and connecting means secured at one end to the other end said flexible means and at the opposite end to said pitman.

4. A device of the character described comprising a supporting member, an oscillating member fulcrumed on said supporting member, power means for said oscillating member, a pitman secured at one end to said oscillating beam and at the opposite end to said power means, a shaft rotatably mounted on said oscillating beam adjacent the outer end portion thereof, sprocket means carried by said shaft, chain means engaging about said sprocket means and secured at one end to a pumping rod, and connecting means secured to the other end of said chain means, said connecting means being secured at one end to said chain means and at the opposite end to a reciprocating element, said connecting means and said chain means being adapted to reciprocate on said beam cooperatively with the oscillation of said beam.

5. A device of the character described comprising an upright supporting member, an oscillating beam fulcrumed on said supporting member, power means, a pitman secured to said oscillating beam and said power means, a shaft transversely mounted on said oscillating beam adjacent the outer end portion thereof, a pair of sprocket members carried by said shaft, a pair of chain strands adapted to ride over said sprocket means and secured at one end to a pumping rod, a pair of elongated bar members secured at one end to the other end of said chain strands and spacedly engaging about the opposite side portions of said supporting member, and swiveled connecting means secured to the other end of said bars for connecting said bars to a reciprocating element whereby to reciprocate said chain strands cooperatively with the oscillation of said beam.

6. A device of the character described comprising an upright supporting member, an oscillating beam fulcrumed on said supporting member, power means, a pitman connected to said oscillating member and said power means, a rotatable shaft transversely carried by said oscillating member adjacent the outer end portion thereof, a plurality of sprocket members carried by said shaft, a plurality of chain strands engaging said sprocket means and secured at one end to a pumping rod, and adjustable connecting means secured to the

other end of said chain strands, said connecting means engaging said chain strands at one end thereof and at the opposite end engaging a reciprocating element whereby to impart reciprocal movement to said chain strands coactively with the movement of said pitman.

7. A device of the character described comprising an upright supporting member, an oscillating beam fulcrumed on said supporting member, power means for said oscillating member, a pitman connecting said power means and said oscillating member, a rotatable shaft transversely mounted on said oscillating beam adjacent the outer end thereof, rotatable means carried by said shaft, flexible means engaging about said rotatable means and secured at one end to a pumping rod, and connecting means adjustably carried by said pitman and engaging the other end of said flexible means whereby to adjustably impart reciprocal movement to said flexible means cooperatively with the swinging movement of said pitman.

25 8. A device of the character described comprising an upright supporting member, an oscillating beam fulcrumed on said supporting member, power means for said oscillating member, a pitman connected at the upper end thereof to the inner end portion of said oscillating beam and at the lower end to said power means, rotatable means carried by said oscillating member adjacent the outer end portion thereof, flexible means engaging said rotatable means, a transverse bar connected to one end of said flexible means, said transverse bar engaging a pumping rod, and adjustable means connected to the other end of said flexible means, said adjustable connecting means being adapted for reciprocal movement cooperatively with said pitman whereby to impart reciprocal movement to said flexible means, said adjustable means being adapted to be adjustably positioned at the other end on said pitman.

In testimony whereof we hereunto affix our signatures.
